(57) **CLAIM**

The ornamental design for a faceplate for a dispenser, as shown and described.

DESCRIPTION

FIG. 1 is an isometric view of a front, top, and left side of an ornamental design for a dispenser and faceplate therefor; FIG. 2 is a front elevational view of the dispenser and faceplate of FIG. 1;

FIG. 3 is a rear elevational view of the dispenser and faceplate of FIG. 1;

FIG. 4 is a left side elevational view of the dispenser and faceplate of FIG. 1;

FIG. 5 is a right side elevational view of the dispenser and faceplate of FIG. 1;

FIG. 6 is a top plan view of the dispenser and faceplate of FIG. 1;

FIG. 7 is a bottom plan view of the dispenser and faceplate of FIG. 1;

FIG. 8 is an isometric view of a front, top, and left side of an ornamental design for a faceplate for a dispenser;

FIG. 9 is a front elevational view of the faceplate for a dispenser of FIG. 8;

FIG. 10 is a rear elevational view of the faceplate for a dispenser of FIG. 8;

FIG. 11 is a left side elevational view of the faceplate for a dispenser of FIG. 8;

FIG. 12 is a right side elevational view of the faceplate for a dispenser of FIG. 8;

FIG. 13 is a top plan view of the faceplate for a dispenser of FIG. 8; and,

FIG. 14 is a bottom plan view of the faceplate for a dispenser of FIG. 8.

The broken lines are included for the purpose of illustrating environmental structure and form no part of the claimed design. The rear elevation views shown in FIG. 10 forms no part of the claimed design.

1 Claim, 10 Drawing Sheets
